Inventor:

J. A. Mac Kinnon

JOHN A. MACKINNON, OF CLEVELAND, OHIO.

Letters Patent No. 83,294, dated October 20, 1868.

IMPROVED HOLD-BACK FOR CARRIAGES.

The Schedule referred to in these Letters Patent and making part of the same.

To all whom it may concern:

Be it known that I, JOHN A. MACKINNON, of Cleveland, in the county of Cuyahoga, and State of Ohio, have invented certain new and useful Improvements in Hold-Backs for Carriages; and I do hereby declare that the following is a full and complete description of the same, reference being had to the accompanying drawings, making part of this specification, in which—

Figure 1 is a side view of the hold-back.

Figure 2, a view of the top.

Figure 3, a longitudinal section.

Figures 4 and 5, detached sections.

Like letters of reference refer to like parts in the different views.

The nature of this invention relates to a device for holding back a carriage in descending a hill, or on backing the same, and which, when the horse is unhitched from the whiffletree, will become self-detaching.

In fig. 1, A represents a section of a carriage-thill, to which the apparatus is attached, and which consists of a hook, B, a vertical section of which is shown in fig. 3.

It will be seen that the base and finger of the hook are hollow or chambered, and that, in the front end of the base, is pivoted a tongue, C, having its free end directed inwardly, the purpose of which will herein-after be shown.

D is a yoke, in which is fixed a double arm, E, the relative position of which, to the yoke, is shown in figs. 4 and 5.

At the opposite end of the yoke is a loop, F, whereby the hook is strapped and attached to the harness.

The practical operation of this device is as follows:

Figs. 1 and 2 represent the yoke in its connection with the hook, and as in practical use. In this position, it will be observed that the lower lip of the arm is projected under the tongue, as shown in fig. 3, and that the tip of said tongue reaches up to and presses against the central part of the arms. Now, as the tongue cannot be turned further upward, nor can it be turned down while the arm is under it, it will be obvious that the yoke will remain in its connection with the hook, as it cannot slide back out of the hook, in consequence of the present position of the tongue.

In order to detach the yoke from the hook, the position of the yoke is reversed. Thus, on turning it upward, in the direction of the dotted line *a*, fig. 3, the

upper lip of the arm will be brought to the end of the finger of the hook, and, at the same time, will depress the end of the tongue until it comes under the arm, over which the yoke can now be easily slipped from the hook.

It will be obvious, that in this position the yoke must be held, in order to reinsert the arm in the hook, and which, when in, on turning it down, as shown in the drawing, the tongue will again take a position that will prevent the disengagement of the yoke, as above said.

This device for hitching the hold-back straps to the thills, is simple, neat, and convenient to manipulate. It is perfectly secure in its ordinary use, and should the horse become detached from the whiffletree by fright, or, in the ordinary course of unhitching him from the carriage, the hooks will, of themselves, uncouple, and thus prevent danger, and save time and labor in unhitching the hold-back straps.

It will be observed that there is a spring, H, fig. 3, located at the base of the hook.

It will also be seen that the hook is attached to the thill by means of band I, which surrounds the thill, and is secured thereto by the key J. By this means, the hook can be moved along on the thill, and adjusted to any desired place; hence, dispensing with the use of screws or bolts driven into the wood as a means of fastening the hook.

I do not claim the spring H, nor any eccentric-cam, in my device; but

What I claim, and desire to secure by Letters Patent, is—

1. The loop F and yoke D, arranged at right angles to each other, or nearly so, the latter passing around hook B, and provided with the bar, having arms, E, substantially as and for the purposes set forth.

2. The continuous band I, attached to the hook, in combination with the key J and shaft A, substantially as and for the purpose set forth.

3. The loop F and yoke D, provided with the cross-bar and arms E, in combination with the hook B and tongue C, substantially as and for the purpose set forth.

JOHN A. MACKINNON.
